ADAPTER ADJUSTMENT ATTACHMENT DEVICE
FOR A SHAFT COUNTERSUNK IN A THREADED
SLEEVE

William H. Hathaway, Jr., 1209 Orkney Drive,
 Virginia Beach, Va.
 Filed Jan. 22, 1964, Ser. No. 339,432
 1 Claim. (Cl. 287—104)

This invention relates to an adapter adjustment attachment device for use in adjusting a shaft such as a valve shaft where the end of the shaft is countersunk within an external sleeve, particularly in locations where the end of the valve shaft is in a location that is difficult to reach.

A particular object of this invention is to provide an adapter tool for adjusting the valve shaft that controls the superheat on an "Alco" Thermal Expansion Valve, such as manufactured by the Alco Valve Company, of St. Louis, Missouri. This "Alco" valve has a male flare threaded connection or externally threaded sleeve on its side in which an adjustment slotted screw head is countersunk. This threaded flare sleeve comes from the factory with a flare or internally threaded cap to prevent loss of refrigerant.

The superheat of this valve is adjusted by removing the flare cap and by taking a screw driver and turning the adjusting screw either clockwise or counterclockwise. When the valve is installed into a system or piece of equipment it is quite often impossible to get a screw driver into position to make any adjustment, due to pipes, lines, and close quarters. In these cases, the service man usually resorts to an off-set screw driver or ratchet type angle screw driver. Even then, it is extremely difficult or almost impossible to keep the screw driver bit in the kerf of the adjusting screw or valve shaft while making an adjustment, and the kerf is usually progressively damaged until it becomes impossible to make the proper adjustment.

It is an object of this invention to overcome these difficulties by providing a construction whereby a screw driver bit may be positively inserted into and held in the valve shaft kerf while making the necessary adjustment without possibility of damaging the kerf or the possibility of the bit slipping or damaging the kerf, and which may be done easily in very close quarters.

A further object of this invention is to provide an adjustment attachment for this purpose which cooperates with a conventional ratchet wrench enabling positive control in making the adjustment.

With the above and related objects in view, this invention consists in the details of construction and combination of parts as will be more fully understood from the following description, when read in conjunction with the accompanying drawings in which:

FIG. 1 is a perspective view of the adapter of this invention.

FIG. 2 is a bottom plan view of FIG. 1.

FIG. 3 is a top plan view of FIG. 1.

FIG. 4 is a sectional view on line 4—4 of FIG. 3, in initial position.

FIG. 5 is a similar sectional view, in operative position.

FIG. 6 is a side elevational view of the invention in operative position with an operating wrench applied.

FIG. 7 is a view at right angles to FIG. 6.

There is shown at 10 the housing for a thermal expansion valve of conventional construction having a valve adjustment shaft 12, which has a screwdriver bit receiving kerf 14 in its end 16, this kerf end 16 being countersunk with an externally threaded connection or sleeve

18. The other end of the shaft 12 may be threaded as at 13 in FIG. 4 when the valve on the shaft 12 is a needle or gate valve, and has a maximum closed position beyond which it may not be turned without causing damage thereto. The shaft 12 is not threaded, as in FIG. 3, when the valve thereon is a butterfly or flap valve. To prevent the possibility of refrigerant leaking from about the adjustment shaft 12, a cap (not shown) is normally threaded onto the threaded sleeve 18. Usually, such cap and sleeve are located in close quarters, where the cap is readily accessible to a wrench, at right angles to the shaft, and where there is no room to insert the bit of an ordinary screwdriver in the shaft kerf 14, countersunk within the end of the threaded sleeve 18.

15. With this invention, a conventional ratchet wrench 36, such as normally available in every service man's tool kit, is used for making the adjustment of the valve shaft 12. This invention includes a cap 20, internally threaded at 22 complementary to the threads on the sleeve 18, and journaled axially through the cap 20 is a tool shank 24. Except for the presence of the axial shaftway through which the tool shank 24 is journaled, the cap 20 is identical with the cap (not shown) which is normally threaded on the sleeve 18 to prevent leakage of refrigerant about the valve shaft 12.

20. An outwardly extending flange 26 on the end of the tool shank 24 is provided with a screwdriver bit 28 of a size complementary to the kerf 14 on the valve shaft 12, so that, when properly inserted in the valve shaft 30 kerf 14, rotation of the tool shank 24 will control rotation of the valve shaft 12.

25. A compression spring 30 coiled about the tool shank 24 between the inside of the cap 20 and the back of the flange 26 biases the tool shank 24 in a direction inwardly of the cap, such inward movement being limited by a stop member in the form of a washer flange 32 fixedly secured on the tool shank 24 outside the cap 20. When the shaft 12 is threaded at 13, for a needle or gate valve, the stop washer flange 32 may be so located 30 on the shaft 12 that it will contact the cap 20 when the valve is at the optimum closed position to warn the operator not to turn any further. Between the outside washer flange 32 and the back of the tool shank end flange 26, the tool shank 24 is cylindrical in shape so that it may rotate freely as well as move axially through the cap 20 within the limits provided by the compression spring 30 and the washer flange 32.

35. Beyond the outside washer flange 32, the tool shank 24 is squared as at 34, preferably about $\frac{1}{4}$ inch on a side so as to be complementary to a socket 38 or 40 in an end wrench 36 of the same size, particularly such as the conventional socket wrench 36 which has the usual rotary ratchet socket 38 in one end, and the fixed socket 40 in the other end, of the $\frac{1}{4}$ inch size.

40. In operation, in order to adjust the valve shaft 12, the flare cap is first removed from the threaded sleeve 18 and the adapter cap 20 is threaded on the sleeve 18 until the screwdriver bit 28 abuts the end of the shaft 12, but probably is not in alignment with the kerf 14, as shown in FIG. 4, with the washer flange 32 moved away from the back of the flare cap 20, which is readily visible to the service man, the spring 30 compressing as the cap 20 moves into position. When the service man becomes aware of this gap between the washer flange 32 and the back of cap 20, either visually or by feel, he then merely rotates the squared end 32 of tool shank 24 until it snaps inwardly under force of the spring 30 as the bit 28 enters the kerf 14. Then, with the bit 28 held in position in the kerf 14, the service man, with the aid of either socket end 38 or 40 of his ratchet wrench 36, as he finds it appropriate, adjusts the valve

by rotating the valve shaft 12 in either direction as necessary to make the proper adjustment, this being very easy because the wrench 36 provides complete control of the rotation of the valve shaft 12 without possibility of the bit 28 slipping out of the kerf 14. Then, when the valve shaft 12 has been properly adjusted, the cap 20 is removed, unthreading it with another wrench, if necessary, while using the wrench 36 to maintain the tool shank 24 and thus the valve shaft 12 against accidental rotation as the cap 20 is removed, so that the bit 28 is removed in an axial direction without accidental rotation. When the cap 20 is removed, the regular flare protecting cap (not shown) is replaced to prevent loss of refrigerant.

Although this invention has been described in considerable detail, such description is intended as being illustrative rather than limiting, since the invention may be variously embodied, and the scope of the invention is to be determined as claimed.

Having thus set forth and disclosed the nature of this invention, what is claimed is:

A valve shaft adjustment attachment device for use in rotating a valve shaft having a tool cooperating end countersunk within an externally threaded sleeve by a wrench extending at right angles thereto, said valve shaft adjustment adapter comprising an adapter cap threaded complementary to the threaded sleeve, a tool shank journaled through the closed end of and terminating within said threaded adapter cap; a valve shaft end cooperating tool fixed on the inner end of said journaled tool shank and also terminating within said threaded cap, said end cooperating tool having a greater diameter than said journaled tool shank, a spring about said journaled shaft biased between said tool end and the inside wall of said cap, a flange fixed to said journaled shaft outside of said cap limiting the axial inward movement of said journaled shaft under the bias of said spring, and a wrench

5
10

cooperating end formed on said journaled tool shank beyond said flange fixed thereon, whereby when said adapter cap is threaded onto the threaded sleeve, said tool end, biased by said spring, will move into contact with the tool cooperating end of the valve shaft and then will yieldably permit said tool shaft to move outwardly of said adapter cap, creating a gap between said flange and the back of said adapter cap, and then rotation of said tool shank will align said valve shaft and tool end and said tool shank will move inwardly, eliminating the gap, and the further rotation of said tool shaft shank by a wrench at right angles thereto will simultaneously rotate and adjust the valve shaft.
